UNITED STATES PATENT OFFICE.

JOHN R. OISHEI, OF BUFFALO, NEW YORK, ASSIGNOR TO TRICO PRODUCTS CORPORATION, OF BUFFALO, NEW YORK.

RADIATOR CAP.

Application filed April 28, 1925. Serial No. 26,398.

This invention relates to radiator caps or closure devices for automobile radiators or the like, and more particularly to radiator caps of the bar type which heretofore have been made of castings which are relatively expensive in initial cost and require the expenditure of a great deal of time and labor in the finishing.

The objects of the present invention are to provide a radiator cap of the so-called bar type of very simple construction and which is relatively light in weight and inexpensive to produce. Further objects are to provide a radiator cap, the principal portions of which may be readily formed of metal stampings; and also to provide improvements in radiator caps in the other respects hereinafter set forth and claimed.

In the accompanying drawings:

Fig. 1 is a side elevation of a radiator cap or closure device embodying the invention.

Fig. 2 is a longitudinal sectional elevation thereof on line 2—2, Fig. 3.

Fig. 3 is a bottom plan view thereof.

Fig. 4 is a plan view of the frame member of the device, with the cap member omitted.

Fig. 5 is a bottom plan view of the cap member before being attached to the frame member.

According to the present invention, instead of constructing the radiator cap of one or more pieces of cast metal, the cap of the present invention is preferably made as follows:

There is provided a cup or closure member 10 which is formed with an annular portion 11 provided with threads 12 adapted to engage the threads on the usual collar (not shown) of the radiator. The cap also has a top closed portion of any suitable outline, such as the annular top portion 14, see Figs. 1 and 2. This top is so formed as to leave a shoulder 15 extending beyond the annular portion 11.

The cap may be made of any suitable material, and the top 14 thereof may be nickel plated or provided with any desirable or attractive finish. The device further includes a frame or frame member 16 having a pair of horizontal, lateral, channeled arms 17 and a central annular or ring portion 18 which is complementary to the portion 11 of the cap. The frame member 16 may be readily stamped from suitable material such, for example, as sheet steel or other metal.

Suitable and novel means are provided for connecting the frame member 16 to the cap or cup 10. In the form shown, the cap is provided with lugs or parts 19 which, when the cup member is formed, extend laterally from the lower edge of the annular portion 11 at diametrically opposite sides of the cup.

In assembling the device, the cap portion 11 is press fitted into the central annular portion 18 of the frame until the shoulder 15 engages the top edge of said portion 18, and the lugs 19 are then bent to extend upwardly between the sides of the channels 17 of the frame, as shown in Fig. 2. When thus assembled the ends of the lugs 19 engage the under side of the channel webs of the arms 17 and prevent separation of or relative rotary movements between the cap and frame member.

The caps may be readily formed of any suitable metal such for example as brass, in a minimum number of stamping operations, and the frame members may be readily stamped in large quantities from any cheap metal and given a suitable finish, and when the parts are assembled as described, a neat and attractive article results.

I claim as my invention:

1. A radiator cap comprising a frame member having handle portions thereon, a cap member having parts for engaging parts of a collar surrounding the radiator opening, one member having a recess and a lug projecting from the other member and bent backwardly thereover to form an outstanding shoulder extending into the recess for maintaining said frame member connected to said cap member and preventing relative movements therebetween.

2. In a radiator cap, a cap portion having parts for engaging the collar surrounding the opening through a radiator for closing said opening, a sheet metal, stamped frame member receiving said cap portion, and interengaging parts on said frame member and said cap at diametrically opposite points on the periphery of the latter whereby said frame member is maintained connected to said cap.

3. In a radiator cap, a cap portion having parts for engaging parts of a collar surrounding the radiator opening, and a stamped sheet metal frame member having a central opening receiving said cap por-

tion, the wall of said frame member opening being interlocked with said cap member.

4. In a radiator cap, a cap member having parts for engaging parts of a collar surrounding the radiator opening, a stamped sheet metal frame member having a central opening receiving said cap member, and bendable means on one of said members for interlocking the two members together 10 against relative rotation.

5. In a radiator cap, a metal frame member having a central portion and side portions projecting from said central portion, said side portions being in the form of channels opening downwardly, a cap member carried by said central portion for closing the opening through a collar on a radiator, and parts on said cap member extending into said channels and engaging the side 20 walls of said channels for preventing relative rotation between said frame member and said cap.

6. In a radiator cap for automobiles and the like, a stamped metal frame member 25 having a central portion and oppositely extending arms in the form of channels opening downwardly, a cap member carried by the central portion of said frame and adapted to close the opening through a collar on the automobile radiator, lugs on said cap member engaging said frame member and extending into the channels of said side arms for preventing relative rotation between said cap member and said frame 35 member.

7. A radiator cap comprising a frame member consisting of a cylindrical portion and a handle portion extending outwardly therefrom, and a cap member receivable by 40 and seating on the upper side of said cylindrical portion and having a common means interlocking with and engaging the under side of said frame member for securing said cap member both against displacement 45 from and against rotation on said frame member.

8. A radiator cap comprising a frame member consisting of a cylindrical portion having outwardly extending recessed handles, a cap member seating on the cylindrical portion of said frame member and having a part fitting within the same, and means for interlocking said part to said

frame member, said means engaging in the recesses of said handles.

9. A radiator cap comprising an annular frame member having outwardly extending handles provided with recesses opening through said annular frame member, and a cap member seating upon said annular frame member and having a part extending therewithin; said part carrying means adapted to be moved outwardly into the handle recesses for interlocking said members together.

10. A radiator cap comprising an annular frame member having outwardly extending handles provided with recesses opening through said annular frame member, and a cap member seating upon said annular frame member and having a cylindrical part fitting therein, the free edge of said cylindrical part having lugs adapted to be bent outwardly and upwardly into the handle recesses for interlocking said members together.

11. In a radiator cap, a metal frame member having a central portion provided with oppositely extending channels, a cap member carried by said central portion, and 80 interlocking means engaging in the oppositely extending channels and connected to the cap member for interlocking said members together.

12. A radiator cap comprising a stamped sheet metal frame having an annular portion and outwardly extending channeled handles, a cap member having a peripheral shoulder set on said annular portion and a part bendable out into the channels of the 90 handles for interlocking the two members together.

13. A two-part radiator cap, comprising in its entirety, an integral closure member, and an integral frame member having a 95 hand grip portion, said closure member having an annular portion embraced by said frame member, one of said members having an open bottomed recess and the other of said members having a projecting 100 lug bent backwardly onto its member to form a shoulder for engaging in the recess to interlock the two members together, said lug being accessible through the open bottom of the recess.

JOHN R. OISHEI.
